KNITTED FABRIC

Fredric L. Aibel, Brooklyn, N. Y.

Application October 24, 1951, Serial No. 252,913

7 Claims. (Cl. 66—195)

1

This invention relates to knitted fabrics of mesh formation and of net characteristics having a lace-like appearance.

Net fabrics have until comparatively recently been made exclusively on special lace or bobbin-net machines. Because of the high labor cost entailed in the operation of such machines, their use has generally been confined to countries where wages are relatively low; and they were accordingly not generally commercially used in the United States.

Attempts have been made to produce on knitting machines netting simulating the product of net machines, because of the lower operating cost of conventional knitting machines. While this has resulted in some success in the production, in this country, of knitted fabrics with mesh characteristics, the disadvantages of the knitting methods employed in this connection have been sufficiently serious as not to enable the netting produced thereby to be commercially competitive with the products of the lace machines, either from a cost or a structural viewpoint.

Two general knitting methods have heretofore been employed in the production of netting simulating the products of bobbin-net lace machines. One method employs half-gauge knitting with two bars, each bar knitting at every course. The other method employs full-gauge knitting with two bars, one bar knitting at every course, and the other bar laying-in at every course. These methods are employed in conjunction with warp or Raschel machines, the construction of which is well known to those skilled in the art.

Although the said first method enables the production of netting with either diamond or hexagonal net formations during the actual knitting process, it has the disadvantage of producing a relatively heavy and narrow product, and is otherwise not economical and commercially competitive with the imported bobbin-net laces.

The second method above mentioned produces a wider fabric, and with more yards per pound of yarn than the first method, but it has several disadvantages which seriously impair its commercial use. It produces only a hexagonal mesh, whereas the conventional bobbin-net product is generally diamond-shaped; and since the purchasing public is accustomed to diamond-shaped netting, there is obviously sales resistance to the hexagonal product. Furthermore, the netting of the said second method is knitted as an irregular mesh, and assumes a regular hexagonal shape only when stretched during a subsequent finish-

2

ing operation, after the fabric is removed from the machine. And in such apparatus it is important that the back beam tension be properly set, since varied or improper tensions result in a distorted pattern that cannot possibly be made truly hexagonal in the finishing. Still another disadvantage of the said second method resides in the fact that it employs inlay threads which intermesh with and run in zigzag fashion through the knitted stitches of the front bar; and since these threads are not locked, it is possible to snag the ends thereof and produce flaws throughout the fabric. Another disadvantage of the last-mentioned knitting method for producing netting is that it is not effectively employable with conventional stop-motion devices which are sensitive to holes, and can accordingly stop knitting machines only when a hole is formed. Since in said second method an end out in the back beam makes a run rather than a hole, the conventional stop-motion machine is ineffective and frequently results in yards of material having runs therein.

It is primarily within the contemplation of this invention to obviate the use of lace-making machines by employing a warp type of knitting machine to produce a fabric in which the basic advantages of each of the said two prior knitting methods are retained, whereas the aforesaid shortcomings thereof are eliminated. More specifically, it is an object of my invention to produce a relatively wide fabric with a maximum yards of material produced per pound of yarn, and to enable the production selectively either of a diamond or hexagonal netting construction during the knitting process, rather than during the finishing process after the product is removed from the machine.

It is a further important object of my invention to present a fabric with uniformly shaped meshes, each containing locked threads, and without the danger of a snagging of the ends to produce runs or other fabric flaws.

And it is within my contemplation to enable said knitted netting to be produced on conventional warp or Raschel machines, or even on modified machines for the production of tricot fabric, merely by employing certain formulas for two chains, in conventional manner.

In the production of the various fabrics of my invention, at least two bars are employed that are capable of wrapping around a needle, so as to perform a knitting or stitch function in conventional manner, full-gauge construction being employed with yarn being supplied from two

bars. A pair of threads, one from each bar, is deployed between two adjacent needles according to formula.

The basic requirements for the production of the various fabrics of my invention are: (1) that only one bar knits at any course—the back bar floating or laying-in when the front bar knits, and the front bar floating when the back bar knits; and (2) that a pair of threads, one derived from each of the two bars, make, in the series set-up, one or more stitches on two adjacent needles.

During the operation of a machine wherein there are the above-mentioned basic requirements, there results a coalescence of certain stitches and a subsequent elongation of others. By combining stitch courses with float or inlay on both bars, there is effected a change in length of certain stitches, that is, there is a distortion of the stitches due to the take-up action and the uniform tension, all in a manner to make the fabric lose "knit" characteristics and assume "net" characteristics. The final fabric contains a locked symmetrical mesh free from irregularity, the legs of the polygon constituting the net formation being joined together at well-defined junctions. The said final product is a knitted fabric which so closely resembles a conventional netting as to make the knitted structure thereof not readily discernible even to experienced knitters.

Referring to the drawings,

Figure 1 is an enlarged diagrammatic view of one form of fabric according to my invention, showing the formation of loop, inlay and float elements in their theoretical undistorted and unstretched condition.

Figure 2 is a diagrammatic view substantially like Fig. 1, but showing the fabric elements in their stretched condition substantially as they appear while being knitted, the diamond-shaped mesh formations being shown considerably enlarged.

Figure 3 is a plan view, in semi-diagrammatic form, of a portion of the completed fabric of the structure shown in Fig. 2, this view being considerably reduced from Fig. 2, but being larger than actual size, and

Figure 4 is an enlarged diagrammatic view, substantially like Fig. 2, but showing another form of fabric.

For illustrative purposes, the drawings show a number of vertical rows or series of looped, floated and laid-in yarn. In Fig. 1, for example, the rows are identified by the reference numerals I, II, III and IV, it being understood that a multiplicity of such rows are simultaneously formed during the knitting process to make the completed fabric. Two threads are employed for forming these rows, these pairs of threads being designated as A₁ and B₁, A₂ and B₂, and A₃ and B₃, respectively. It will here be assumed that A₁, A₂ and A₃ are front bar threads, and B₁, B₂ and B₃ are rear bar threads. The horizontal courses are designated by the reference letters, T, U, V, W, X, Y, Z.

During the knitting operation, the thread A₁, in emerging from previously formed loop 10_a in course T, is formed by the front bar into the loop 11_a in course U, and at the same time the thread B₁ is laid-in by the rear bar in the same course, the laid-in portion being designated 12_a. In the next course V, a stitching operation is formed on thread B₁, to form the loop 13_a; and at the same time the thread A₁ is made to float

during the course, the floating portion being designated 14_a. Thread A₁ is then knitted into the loop 15_a in the course W; and at the completion of this course, section 16_a of thread A₁ is carried to row II (that is, to an adjacent needle around which it is operatively wrapped in conventional manner) and formed into loop 17_a in said row II, course X. While the last-mentioned action takes place, section 18_a of yarn B₁ is floated and carried to row II and laid in at 19_a in said row X. Thread B₁ is then knitted to form the loop 20_a at course Y in the same row, while section 21_a of thread A₁ is floated through course Y and then knitted to form the loop 22_a, whereafter section 23_a thereof is carried back to row I to form loop 24_a in the next adjacent course. This process is continued in subsequent courses by repeating the steps described with reference to formation of the said previously made loops, such as 11_a, 13_a and 15_a in courses U, V and W, and the floats and laid-in portions of the threads associated therewith.

Similarly, yarns A₂ and B₂, and A₃ and B₃ are looped, floated and laid-in to form the portions of the fabric comprised of rows II, III and IV, and as many other rows as can be formed by the needles on the machine. The loops, floats and laid-in sections in rows II, III and IV are designated by reference numerals analogous to their respective counterparts above described, whereby it will be unnecessary to repeat the description for all the illustrated rows. Suffice it to say that loops 10_b, 10_c, 11_b, 11_c, 13_b, 13_c, 15_b, 15_c, 15_d, 17_b, 17_c, 20_b, 22_c, 24_b and 24_c correspond to previously described loops 10_a, 11_a, 13_a, 15_a, 17_a, 20_a, 22_a and 24_a; and that the floats, laid-in and other sections 12_b, 12_c, 14_b, 14_c, 16_b, 16_c, 18_b, 18_c, 19_b, 19_c, 21_b, 21_c, 23_b and 23_c correspond to the previously described analogous sections 12_a, 14_a, 16_a, 18_a, 19_a, 21_a and 23_a.

In order to readily be able to follow the intermovement of the various threads from the formation of loops, floats and laid-in sections to the final desired mesh formation, it should be borne in mind that in the structure above described, the arrangement of the components of the rows and courses illustrated in Figure 1 is merely diagrammatic, and shows the fabric elements in their theoretically unspread condition. Actually, during the knitting process tension is continuously being applied to the fabric elements being formed, so that there is an inter-sliding movement between adjacent interengaged thread sections, whereby the appearance of the loop, float and inlay sections is substantially like that illustrated in Fig. 2.

More specifically, the knitting tension causes a shortening of certain interknitted loops and a corresponding elongation of the diagonally carried-over laps and laid-in or float sections, as well as an elongation of adjacent loops in the same course extending from floated yarn, there being accordingly pairs of elongated portions forming the four sides of a diamond-shaped mesh configuration, and the shortened loops virtually coalescing into what may be regarded as knots tying together the terminals of said sides. In other words, although there is uniform tension throughout the fabric elements being knitted, there is actually a distortion of the fabric whereby it no longer resembles a knitted fabric but rather a net fabric that looks closely like the product of bobbin-net machines.

Thus, by referring to Fig. 2, it will be seen that in the operatively stretched fabric containing the

vertical rows of wales V, VI, VII, VIII, IX and X, there has been a contraction of the loops 11a, 13a, and 17a, 20a, for example, as well as of the corresponding loops 11b, 13b, and 17b, 20b, and 11c, 13c, and 17c, 20c, the contracted or coalesced pairs of loops extending in parallel horizontal rows such as rows R and S the loops of each pair being in adjacent parallel courses. Between adjacent parallel pairs of the coalesced loops, along rows R and S for example, are the elongated thread portions that form the legs of the said diamond formations. These elongated portions are, for example, the diagonally-carried-over lap section 16b and the float section 18b, forming one side of the diamond D; adjacent loop 15b on the same course forming a second side of the diamond; the diagonally-carried-back lap section 23b and the float section 25b forming a third side of the diamond; and the adjacent loop 22a on the same course forming the fourth side of the diamond. It is apparent that all other diamond formations are produced in the same manner.

It will be clarifying to note that if the arrows K, L, M and N indicate the opposing pulls that cause tension in the respective sections 16b, 15b, 12b and 10b, the pairs of the loops in rows S and R are contracted due to these pulls, whereas the carried-over lap sections and loops, such as lap 16b and loop 15b for example, extending from unknit float 14b, are elongated, together with unknit float 18b, by the contraction of said pairs of loops. In other words, the slack caused by the contraction of said pairs of coalescing loops is taken up by thread sections that are either directly extending from or are themselves unknit laid-in or floated thread sections.

The fabric of Fig. 2 is obviously greatly enlarged. In actual size the coalesced locked loops are visible only as fine junctures for the well-defined sides of the diamond formations, in view of the fine denier yarns that are used for this fabric. The finished product is a locked symmetrical mesh, of lace-like appearance; and the product comes off the machine in finished shape.

In Figure 4, which shows another form of fabric according to my invention, a plurality of pairs of threads E₁ and F₁ are employed, these being respectively front and rear bar threads. This fabric contains the vertical rows or wales XI, XII, XIII, XIV, XV, XVI and XVII, and horizontal rows or courses O, G, P, H and Q. Considering the thread elements that make up the diamond formation D₁, for example, it will be necessary to follow the threads in wales XIII, XIV and XV.

Thread E₁, extending through previously formed loop 26, is formed into a loop 27 at course 0 in wale XIII, and at the same time thread F₁ is laid-in at 28. The lap 29 is then carried over as a float to the next adjacent wale XIV and stitched into a loop 30. In the meantime the extension of laid-in portion 28 is formed into loop 31 which extends diagonally into wale XII and interloops, at course P, with the loop 32 in said last-mentioned wale, the opposite lap 33 of loop 31 being carried over diagonally to wale XIV and being laid-in at 34 in course P. Lap 35 of loop 30 is then carried back to wale XIII and stitched into loop 36 which is interlooped at course Q with loop 37 extending diagonally from wale XII.

It will be noted that thread 29 is a float, and that thread section 33 is a lap of loop 31 which extends from laid-in portion 28, thereby accounting for the elongation of said thread sections 29

and 33 upon the operative contraction of loops 27 and 30—to form one side of the diamond D₁. It will similarly be noted that the other sides of the diamond are formed from threads which are either themselves floats, or which extend from floats or laid-in portions.

It will further be noted that in both forms of the fabric herein illustrated, as well as in many other forms possible within the scope of my invention, there is a certain basic structure. In such basic structure there are a plurality of pairs of warp threads carried over from one wale to an adjacent wale, the two threads of each of said pairs forming loops in each wale at different courses, there being courses in which one of said threads is unknit and not formed into loops. In such courses the said unknit threads are either floated or laid-in.

For example, in Figure 2, the pair of threads A₂ and B₂ have portions 16b and 18b, respectively, carried over from wale VII to adjacent wale VIII, portion 16b forming loop 11b in wale VIII at course X, and portion 18b forming loop 20b in course Y, portion 19b of thread B₂ being unknit (and being laid-in) in course X, and portion 21b of thread A₂ being unknit (and floating) in course Y. Similarly, in Figure 4, one of the pairs of threads E₁ and F₁ have portions 29 and 33, respectively, carried over from wale XIII to wale XIV, portion 29 forming loop 30 in wale XIV at course P, and portion 33 being laid-in, that is, being unknit, at said latter course. By referring to wale XIII, it will also be noted that terminal loop portion 38 of portion 37 of an F₁ thread is positioned in said wale XIII at the uppermost portion of course H, lap 35 of thread E₁ being also disposed in course H. Accordingly the structure of Figure 4 conforms to the basic requirement above mentioned, there being a plurality of pairs of warp threads, carried over from one wale to an adjacent wale, there being loops formed by said threads in each wale at different courses, there being courses in which one of the two threads is either floated or laid in.

In forming the fabric of Figures 1 and 2, the following formula is employed:

Chain I: 20, 22, 20, 24, 22, 24

Chain II: 00, 02, 00, 44, 42, 44

In the production of the fabric of Figure 4, the following formula is used:

Chain I: 20, 00, 24, 44

Chain II: 00, 02, 44, 42

Other forms of fabric, as aforesaid, may be made by employing the above-mentioned basic structure, but employing other formulas. For example, to produce a fabric with hexagonal meshes, the following formula may be employed:

Chain I: 20, 22, 22, 20, 24, 22, 22, 24

Chain II: 00, 02, 20, 00, 44, 42, 24, 44

Any of the fabrics produced in accordance with my invention can be readily fabricated by those skilled in the art; and the resulting fabric will have a very well-defined lace-like appearance as well as the other characteristics hereinabove mentioned.

In the description hereinabove given the various threads or yarns are designated as warp threads since they are supplied from warp beams. The carried-over and carried-back portions of the threads, such as 16b and 23b of Fig. 1, are lap portions and they are herein fre-

quently designated as such. Although in warp knitting machines the back bar can either float or lay-in, whereas the front bar can only float, the functions of the laid-in and floated sections of the threads are substantially similar, in this invention, in producing the elongations and contractions above-mentioned. And hence, since such floats and laid-in sections are all unknitted portions of the threads, they are designated in the claims, for convenience, as unknitted floats, regardless of whether or not they are technical floats or laid-in sections.

In the above description, the invention has been disclosed merely by way of example and in preferred manner; but obviously many variations and modifications may be made therein. It is to be understood, therefore, that the invention is not limited to any specific form or manner of practicing same, except insofar as such limitations are specified in the appended claims.

I claim:

1. In a lace-like knitted fabric of substantially uniform polygonal mesh formation, a plurality of pairs of warp threads formed into a plurality of wales and courses, the two threads of each of said pairs forming interengaged contracted loops in wales at different courses, to constitute juncture portions of said polygonal mesh formation, one of the two threads of each of said pairs having floated portions in certain courses and the other of said two threads having laid-in portions in certain other courses, a plurality of pairs of said threads extending from one wale to another wale in a single course to form sides of said polygonal mesh formation.

2. In a lace-like knitted fabric of substantially uniform polygonal mesh formation, a plurality of pairs of warp threads formed into a plurality of wales and courses, the two threads of each of said pairs forming loops in wales at different courses, one of the two threads of each of said pairs being unknitted in certain courses and the other of said two threads being unknitted in certain other courses, a plurality of pairs of thread sections extending diagonally from one wale to another and interengaging said loops, said loops being of contracted formation and constituting the junctures of the sides of the polygonal meshes of said formation, said diagonally extending pairs of thread sections being of relatively extended length and constituting the sides of said polygonal meshes.

3. In a lace-like knitted fabric of substantially uniform diamond-shaped mesh formation, a plurality of pairs of warp threads formed into a plurality of wales and courses, the two threads of each of said pairs forming contracted loops in wales at different courses, one of the two threads of each of said pairs being unknitted in certain courses and the other of said two threads being unknitted in certain other courses, each diamond-shaped mesh comprising four sides interconnected with said contracted loops, said

5 sides each comprising a pair of thread sections, the pairs of thread sections at opposite sides of the mesh comprising, respectively, two sections of one of the said two threads, and two sections of each of the said two threads.

4. In a lace-like knitted fabric of substantially uniform polygonal mesh formation, a plurality of pairs of warp threads formed into a plurality of wales and courses, the two threads of each of said pairs forming contracted and elongated loops at different courses, a plurality of pairs of said threads extending from one wale to another in a single course, one thread of each of said pairs constituting knitted loops in two successive courses, and the other thread of each of said pairs constituting inlaid sections in said two successive courses, said threads which constitute said knitted loops constituting floats, and said other threads constituting knitted loops in the courses respectively preceding and following said two successive courses.

25 5. In a lace-like knitted fabric of substantially uniform polygonal mesh formation, a plurality of pairs of warp threads formed into a plurality of wales and courses, the two threads of each of said pairs forming contracted and elongated loops at different courses, each loop being interengaged with another single loop, one thread of each of said pairs of threads forming a single elongated loop in a polygon of said polygonal mesh formation.

30 6. In a lace-like knitted fabric of substantially uniform polygonal mesh formation, a plurality of pairs of warp threads formed into a plurality of wales and courses, the two threads of each of said pairs forming contracted and elongated loops at different courses, a plurality of pairs of said threads extending from one wale to an adjacent wale in a single course, one thread of each of said pairs having an inlaid portion and the other thread of each of said pairs having a floated portion in a side of a polygon of said polygonal mesh formation.

35 7. In a lace-like knitted fabric of substantially uniform polygonal mesh formation, a plurality of pairs of warp threads formed into a plurality of wales and courses, the two threads of each of said pairs forming contracted and elongated loops at different courses, the junctures of adjacent sides each being formed from a single contracted loop.
